Patented Jan. 28, 1890

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,613, dated January 28, 1890.

Application filed December 26, 1889. Serial No. 335,044. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming part thereof.

10 The leading feature of my design consists of continuous convolutions of bands, forming circles, 1, and connections between them, 2,

the intervening spaces being filled in with branching scrolls 3, which in some places form circular ornaments 4. 15

What I claim is—

The design for a wall and ceiling covering herein shown and described, consisting of bands the entwining of which form circles with an ornamentation of branching scrolls. 20

PAUL GROEBER.
